SOLE FOR SHOES

Max I. Rovick, Chicago, Ill.

Application July 5, 1943, Serial No. 493,628

6 Claims. (Cl. 36—30)

This invention relates to shoes and more particularly to the soles of shoes, especially a sole which may be made as a complete article of manufacture and sale to shoe manufacturers or shoe repairmen.

It is one of the objects of the present invention to provide a shoe sole which will embody a minimum of leather and yet, when incorporated in a shoe and viewed from the side, will present the appearance of an ordinary leather sole.

It is a still further object of the present invention to provide a shoe sole which may be made of non-scarce materials such as, for instance, canvas, and which may be used in the fabrication of shoes in the same manner and on the same machines as present leather soles are used.

It is a still further object of the present invention to provide a shoe sole which may be made of canvas and yet which will have the necessary resiliency, elasticity and wearing qualities.

The attainment of the above and further objects of the present invention will be apparent from the following specification taken in conjunction with the accompanying drawing forming a part thereof.

In the drawing:

Figure 1 is a side view of a shoe embodying the sole of the present invention;

Figure 2 is a bottom view of a shoe sole made in accordance with the present invention;

Figure 3 is a transverse sectional view taken along the line 3—3 of Figure 2; and

Figure 4 is a sectional view taken along the line 4—4 of Figure 1.

In Figure 1 I have shown one standard type of shoe to which the sole of the present invention has been applied, it being understood that the invention is equally applicable to other types of shoes. The shoe of Figure 1, indicated in general by the reference numeral 1, includes a shoe upper 2, and the sole 3 of the present invention. The sole is stitched to a welt 4 which projects from the shoe upper in the usual manner. Since the construction of the shoe upper and the welt projecting therefrom are well known in the art and form no part of the present invention, a further description and illustration thereof is not necessary at this time.

The sole of the present invention consists of a base layer 5 of strong cloth, such as, for instance, canvas or duck suitably treated to waterproof the same, a filler 6 of felt or of sponge material, which may be paper impregnated with asphalt or tar, or other soft filler material, and a top layer 7 of paper. The top layer 7 consists

of a number of sheets of tough paper or the like secured together by thin layers of asphalt, rubber cement or other water-proofing material 9. The intermediate layer or filler 6 of felt is of lesser width than the width of the top and bottom layers. A narrow strip 12 of leather extends around the lower perimeter of the sole. The bottom layer 5, top layer 7 and leather strip 12 are all sewed together by a continuous line of stitching 14. It is to be noted that the line of stitching 14 is adjacent the inner edge of the strip 12 rather than adjacent the outer edge thereof. The edge of the canvas at 16, on the outer side of the line of stitching 14, is coated with a water-proofing material such as, for instance, shellac, as is also the rim of the bottom surface of the layer 7 between the edge of the top layer and the line of stitching 14. This not only waterproofs the edge of the sole but also adheres the crossed strands at the edge of the layer 5 and inhibits unraveling of the strands.

To fabricate the shoe the sole is secured to the welt 4 of the shoe upper 2 by a line of stitching 18 or in any other known manner, as by cementing the sole to the welt. Thereafter a filler 19, of the shape of the inside of the shoe, is placed in the interior of the shoe to bring the top surface of the sole approximately flush with the corresponding surface 20 of the shoe upper. Thereafter an inner sole 21 of the usual construction is placed in the shoe, which inner liner rests on the filler 19 and on the adjacent parts of the shoe upper.

It is to be noted that the lower surface of the base layer 5 is below the lower surface of the rim 12, hence the wear on the sole is at the base layer. Due to the nature of the material of the base layer, consisting of crossed strands, the shoe is less likely to slip or slide on a slippery surface. Sliding may further be inhibited by cutting the base layer 5 that is to be used in the manufacture of the sole, on a bias with respect to the longitudinal axis of the sole, so that all the cords of the base layer are at a substantial angle to the longitudinal axis of the sole. After the base layer 5 has worn the shoe may be resoled by cementing or sewing a leather sole directly to the bottom of the worn sole, leaving the strip or rim 12 in place, as is usual in standard shoe repairing operations.

In compliance with the requirements of the patent statutes I have here shown and described a preferred embodiment of my invention. It is, however, to be understood that the invention is not limited to the precise construction here

shown, the same being merely illustrative of the principles of the invention. What I consider new and desire to secure by Letters Patent is:

1. A shoe outsole comprising upper and lower layers of substantially identical shape, a narrow rim strip along the marginal edge of the lower layer, means securing the two layers and the strip together, and a filler pad of substantially the thickness of the rim strip interposed between the two layers and with the pad terminating short of the securing means so that the securing means does not extend through the pad.

2. A shoe outsole comprising upper and lower layers of substantially identical shape, a narrow rim strip along the marginal edge of the lower layer, a row of stitching securing the two layers and the strip together, and a filler pad interposed between the two layers and with the pad terminating short of the row of stitching so that the stitching does not extend through the pad.

3. A shoe outsole comprising upper and lower layers of substantially identical shape, a narrow rim strip along the marginal edge on the under side of the lower layer, a row of stitching along the edge of the outsole securing the two layers and the strip together, a filler pad interposed between the two layers and with the pad terminating short of the row of stitching so that the stitching does not extend through the pad, and waterproofing means at the edge of the lower layer outside of the loop of stitching.

4. A shoe outsole comprising a lower surfacing layer of fabric, a water-proof adhering coating along the edge of the lower surfacing layer to inhibit raveling of the thread of the fabric, 5 a strip of flexible material extending along the marginal edge of the lower surfacing layer at the bottom surface thereof, and means securing the strip and the surfacing layer together.

5. A shoe outsole comprising a lower surfacing layer of fabric, an upper surfacing layer overlying the lower layer, a filler pad interposed between the two layers, a strip of flexible material extending along the marginal edge of the lower surfacing layer at the bottom surface thereof, and stitching securing the strip and the two surfacing layers together, the filler pad terminating short of the stitching so that the stitching does not extend through the pad, the stitching being located adjacent the inner edge of the flexible strip.

6. A shoe outsole comprising a lower surfacing layer of fabric, a waterproof adhering coating along the edge of the lower surfacing layer to inhibit raveling of the thread of the fabric, an upper surfacing layer overlying the lower layer, a strip of flexible material extending along the marginal edge of the lower surfacing layer at the bottom surface thereof, and stitching securing the strip and the two surfacing layers together.

MAX I. ROVICK.
